PREFABRICATED CERAMIC COMBUSTION CHAMBER

Frank Christenson, Jamaica Estates, N. Y., assignor to Refractory & Insulation Corporation, New York, N. Y., a corporation of New Jersey

Application June 6, 1944, Serial No. 538,900

4 Claims. (Cl. 158—1)

The present invention relates to ceramic combustion chambers for use in liquid fuel burning installations and, more particularly, to ceramic combustion chambers comprising a number of prefabricated wall sections.

One object of the invention is to provide a combustion chamber of this type having simple means for joining the sections together without the use of cement or a similar binder.

A further object of the invention is to provide a joint between adjacent prefabricated sections of a ceramic combustion chamber which will hold the walls firmly in position while the cement floor is poured after the sections have been assembled.

A still further object of the invention is to provide means for securing adjacent prefabricated wall sections together which, after the combustion chamber has been assembled, are completely embedded in ceramic material and thereby protected against the destructive action of the combustion gases.

Another object of the invention is to provide a combustion chamber having generally U-shaped front and rear sections which can be joined together directly or which, if desired, can be used for the erection of a combustion chamber of greater horizontal depth by the interposition between the front and rear sections on each side of the chamber of one or more extension sections, each adapted to be connected with a rear edge of the front section and with a front edge of the rear section.

Still another object of the invention is to provide a prefabricated ceramic combustion chamber in which the rear section has a height exceeding that of the front section and means are provided which permit of said sections of different heights being secured firmly together without the use of cement or the like, even in installations in which the side walls of the combustion chamber have to be arranged in direct contact with the inner walls of the furnace.

These and other objects which will appear more clearly as the specification proceeds, are accomplished according to the invention by the arrangement and combination of elements set forth in the following detailed description, defined in the appended claims and illustratively exemplified in the accompanying drawing in

two extension sections inserted between said front and rear sections.

Fig. 2 is a separate perspective view of an extension section and

Fig. 3 is a perspective exploded view of a combustion chamber similar to that shown in Fig. 1, but without extension sections.

Referring to the drawing, 11 denotes the generally U-shaped front section of the combustion chamber which consists of two half sections 11a and 11b. The two half sections are provided at their adjoining edges with semi-circular cutouts forming, after assemblage, the central firing aperture 12. They are held together by a U-shaped clip 13 having its legs inserted into vertical holes 14a and 14b provided in the top edges of the sections 11a and 11b. The generally U-shaped rear section 15 comprises two half sections 15a and 15b and has a height exceeding that of the front section 11. Each front section 11a and 11b has at its rear end a flat vertical end face 16 and a step portion 17 (see Fig. 3) of equal width projecting from said end face, said step portion having a flat vertical end face and extending from the bottom to a horizontal plane which passes approximately through the center of the firing aperture 12. Each rear section 15a and 15b has a flat vertical end face 18 parallel to the end face of said step portion 17 and a second step portion 19 projecting from the face 18 and extending from said horizontal plane to the top of said rear section. The step portion 19 has a cross section corresponding to that of the step portion 17 and is adapted to complement the latter. The step portions 17 and 19 are provided in their corresponding horizontal faces with vertical holes 20 and 21 respectively and metal dowel pins 22 inserted into the holes 20 and projecting from these holes for about half of their length are adapted to fit into the holes 21 to effect a firm connection between the front and rear sections.

The two halves 15a and 15b of the rear section are joined together in a similar manner along stepped edges 23—24 by means of a dowel pin 25 inserted in registering vertical holes 26—27.

It will be seen that the assembled sections which are connected by the dowel pins 22 and 25 cannot pivot relative to each other, because they abut upon each other on flat surfaces, and, as a result, a structure is obtained which is capable of resisting the outward pressure exerted upon the walls when the cement floor is poured into the assembled wall structure. The resistance of the assembled wall elements against

Fig. 1 is a perspective view of a combustion chamber according to the invention, composed of a U-shaped front section and a U-shaped rear section each consisting of two half sections and

displacement is particularly good if the dowel connection is made in a horizontal plane considerably below the top edge of the wall sections and therefore comparatively close to the level of greatest pressure when the cement is poured.

Another advantage of the construction according to the invention is that the metal dowel pins which are used as connecting elements, are completely surrounded by ceramic material after the wall structure has been assembled and are thus protected against the deteriorating effects of the combustion gases.

A particular advantage of the construction shown is that wall sections of different height which cannot be secured together by U-shaped clips inserted in holes provided in the top edges of the sections, as used for instance for securing together the half sections 11a and 11b, may be firmly connected in a very simple manner by the means provided according to the present invention.

The U-shaped front and rear sections of the ceramic combustion chamber according to the invention may be joined together directly as indicated in Fig. 3, or if desired, they may be used to erect a combustion chamber of greater horizontal depth by inserting between the front and rear sections on each side of the chamber one or more extension sections. Fig. 1 shows an assembled combustion chamber in which one extension section 28 is provided on each side of the chamber. As seen best in Fig. 2, each extension section 28 has a stepped vertical front edge 29 similar to the front edge of the rear section 15a or 15b and a stepped vertical rear edge 30 similar to the stepped vertical rear edge of the front section 11a or 11b. Vertical holes 31 and 32 provided in the horizontal faces of the stepped edges 29 and 30 receive dowel pins 33 which connect the extension section 28 firmly with the front sections 11a and 11b and the rear sections 15a and 15b. The top edge 34 of the extension sections may be sloped from the height of the rear section 15 to that of the front section 11.

I claim:

1. A ceramic combustion chamber having a prefabricated substantially U-shaped front section provided with a central firing aperture, said front section having flat vertical end faces and, projecting from each end face, a step portion of equal width each having a flat vertical end face extending from the bottom to a horizontal

plane considerably below the top edge of said section, a substantially U-shaped rear section having flat end faces adapted to abut against the flat end faces of said step portions and, projecting from each end face of said rear section, a step portion complementary to the adjacent step portion on said front section, and metal dowel pins insertable into registering vertical holes provided in the step portions of said front and rear sections, respectively.

2. A ceramic combustion chamber comprising a prefabricated substantially U-shaped front section having stepped ends each bounded by a flat vertical face extending from the top of said section to a horizontal plane considerably below said top; a horizontal face extending outwardly from said vertical face in said plane, and a second flat vertical face extending from said plane to the bottom of said section, a substantially U-shaped rear section having stepped ends complementary to the stepped ends of said front section, an intermediate wall section on each side between said front and rear sections, each said intermediate section having one of its end faces stepped to fit against a stepped end of said front section and having its other end face stepped to fit against the corresponding stepped end of said rear section, and metal dowel pins inserted in registering vertical holes in the stepped portions of said various sections to connect the same.

3. A ceramic combustion chamber as claimed in claim 1, in which said dowel pins are provided with pointed tips at their upper ends.

4. A ceramic combustion chamber having a prefabricated substantially U-shaped front section provided with a central firing aperture, said front section having flat vertical end faces and, projecting from each end face, a step portion of equal width each having a flat vertical end face and a horizontal face in a plane considerably below the top edge of said section, a substantially U-shaped rear section having flat end faces adapted to abut against the flat end faces of said step portions and, projecting from each end face of said rear section, a step portion complementary to the adjacent step portion on said front section, and metal dowel pins insertable into registering vertical holes provided in the step portions of said front and rear sections, respectively.

FRANK CHRISTENSON.
